UNITED STATES PATENT OFFICE.

WILLIAM M. ROGERS, OF NEW YORK, N. Y.

NONREFILLABLE BOTTLE CAP.

Application filed November 7, 1925. Serial No. 67,594.

This invention relates to improvements in caps for bottles and has for its object to provide a cap for bottles which may be easily and cheaply constructed, easily applied to the neck of the bottle and which provides an adequate protection against refilling when the bottle has been once emptied.

It is often the case that where a manufacturer has put upon the market certain goods exceedingly fine in quality and has built up a large business in that commodity, imitations appear on the market which pass off goods of greatly inferior quality upon the public in containers and under trade names exactly similar to those used by the original manufacturer.

This is particularly true in the case of liquids put up in bottles, as for instance hair tonics, toilet waters, perfume and other liquids, as the empty bottles are easy to procure, and easily refilled with an interior substitute, especially where the hair tonic or the like is dispensed in barber shops, beauty parlors and the like, greatly to the damage of the original manufacturer whose sales are thus interfered with and whose reputation as to the quality of his products is impaired.

It is one of the objects of this invention therefore to provide a cap for bottles such as hair tonic, toilet water, perfume or other bottles which will make it impossible to refill the bottle.

Another object of the invention is to provide a non-refillable cap for bottles which will resist burglarizing and prevent opening of the non-refillable caps without destroying the cap.

Another object of the invention is to provide a non-refillable cap for a bottle which contains a float to adequately seal the mouth of the bottle if it is attempted to force or draw liquid into the bottle when the bottle is in an inverted position.

These objects as well as others which will appear as the description of the invention proceeds, I propose to accomplish while keeping the cost of the non-refillable cap at a minimum, and well within the economic limit which manufacturers of valuable liquids can pay.

Referring now to the drawings.

Figure 1 is an elevational view of a bottle with a cap illustrating one embodiment of my invention.

Figure 2 is a sectional elevational view of the bottle and cap shown in Figure 1.

Figure 3 is a disassembled perspective view of the parts of the cap shown in the order of their assembly.

Figure 4 is an enlarged plan view of the protecting disc shown in Figures 2 and 3.

Figure 5 is an elevational view of the same.

Figure 6 is an enlarged plan view of the float valve shown in Figures 2 and 3; and

Figure 7 is an elevational view of the same.

In the form of embodiment of the invention illustrated, a cap 10 is mounted over the mouth of any suitable bottle 11, having the usual beaded or enlarged rim 12, adjacent the mouth thereof. A tubular outer casing or shell 13, of the cap 10 is constructed of relatively hard metal such as brass, nickel or the like and is adapted to be slipped over the mouth and enlarged rim 12, of the bottle 11, in such a manner that edge 14 of the shell 13 comes below the enlarged rim 12 and may be crimped or turned inwardly thereby grasping the neck of the bottle below the rim 12 and holding the cap 10 tightly and permanently on the top of the bottle 11.

A dispensing spout or nozzle 15 at the top of and integral with the cap 10, is threaded to receive a cover cap 16, having a resilient stopper 17 to close and seal the top of the nozzle 15 when the sealing cap 16 is screwed into place.

The arrangement thus far described is the more or less common type of cap for hair tonic and other bottles with the exception that my cap is made of harder metal to prevent its removal when once installed on the bottle.

The part to prevent refilling of the bottle comprises a cup 18 having a cylindrical well 19 adapted to fit easily into the mouth of the bottle 11, and a flange 20 adapted to rest upon the top of the mouth of the bottle and support the cup 18 therein. The cup 18 has a hole 21 in the bot-

2
tom thereof to permit the liquid in the bottle to run out through the nozzle when the bottle is inverted. A ring or washer 22 of compressible material such as cork is 5 preferably disposed between the flange 20 of the cup 18 and the top of the mouth of the bottle 11 and adequately prevents any of the liquid from leaking therebetween. The washer 22 is made preferably of such a 10 diameter that it will fit snugly between the shell 13 and the walls of the cup 18 to hold the cap frictionally in the shell 13, so that the cap and the parts to prevent refilling of the bottle may be assembled and held together 15 as a unit for convenient securing of the same to the bottle mouth.

A valve or float 23 made preferably of cork or other light material and of a diameter a little less than the inside diameter of 20 the well 19 of the cup 18, is disposed within the well 19 and is free to move longitudinally thereof, and normally covers the hole 21 in the cup 18 when the bottle is in upright position. This valve 23 has a plurality of notches 24 in its periphery adapted to permit liquid from the bottle to flow past the valve when the bottle is inverted.

A protecting disc 25 substantially cylindrical in shape, made preferably of steel 30 and case hardened is carried in the well 19. This disc has a plurality of grooves 26 extending along the sides parallel to the axis thereof and other grooves 27 on the upper end thereof connecting the upper ends of 35 the grooves 26, on the sides. The disc 25 is of a diameter to fit easily within the well 19 of the cup 18, and its length is such that when placed within said cup 18 above the cork valve 23 there is a space 28, permitting 40 the reciprocation of the valve 23 and disc 25 within the well 19 of the cup 18.

The operation of the devices is as follows:

When it is desired to obtain some of the liquid from the bottle 11, the same is inverted as is done with an ordinary bottle having a simple spout or nozzle cap. The disc 25 slides toward the nozzle until it strikes against the upper inside surface of the shell 13 at the base of the spout or nozzle 15. This allows the liquid in the bottle to pass through the hole 21 in the cup 18 and push the float 23, if it has not already been moved, by gravity, against the disc 25. The liquid then passes through the notches 24 in the float 23, through the grooves 26 in the disc 25 and across the top of the disc through the grooves 27 and drips or runs from the spout or nozzle 15. Ordinarily the bottle is given a shaking motion 60 to apply the liquid, drop by drop to the scalp or the like.

When the bottle is righted, the disc 25 slides back to its normal position at the bottom of the well 19, pushing the valve 23 65 before it so that the valve covers the hole

21 in the cup 18 and acts as a seal to prevent evaporation if it is desired not to replace the cover cap 16.

The bottle and cap as described is thus 70 completely non-refillable. Due to the use of hard metal in the shell 13, the cap cannot be removed and replaced upon the bottle without the use of very expensive machinery. The bottle cannot be refilled when in inverted position because the float 23 will 75 rise with the liquid and close the port 21 before any liquid enters the bottle, and the bottle cannot be burglarized by drilling through disc 25 with a drill projected 80 through the hole 15 because the hardened face of the disc and the configuration of the grooves 27 will prevent penetration by the drill and will cause the disc to catch on the facets of the drill and turn there-with in the well 19.

As will be noted from the foregoing description the parts comprising the invention are simple and easily and cheaply made, all can be made with automatic machinery with small cost for materials or labor: the parts are easily assembled, and the assembled cap 13 and cup 18 are held together before applying to a bottle by the snugly fitting compressible ring or washer 22. The invention therefore represents a highly efficient, inexpensive and absolutely non-refillable cap for bottles and inasmuch as many variations and changes of the embodiment of the invention may be resorted to without departing from the spirit of the invention, 95 I do not wish to limit the invention, to the specific embodiment shown but to interpret it as broadly as the scope of the appended claims will permit.

105 I claim:

1. A bottle cap comprising a shaker nozzle having an extension to be permanently secured over standard beading of a mouth of a bottle, a washer to be placed at the edge of the bottle mouth, a cylindrical cup-shaped member having a flange to be secured between said washer and extension, and having an aperture in the bottom thereof, a float valve resting on the bottom of said cup-shaped member, and a case hardened 110 disk disposed between said float valve and nozzle, axially reciprocable in said cup-shaped member to impinge against said float valve and nozzle, and being substantially co-extensive with the internal diameter of said 115 cup-shaped member, and having liquid passages along the edges thereof.

2. A bottle cap comprising a nozzle having an extension to be permanently secured over standard beading of a mouth of a bottle, a washer to be placed at the edge of the bottle mouth, a cylindrical cup-shaped member having a flange to be secured between said washer and said extension, and having an aperture in the bottom thereof 120

125

130

of smaller diameter than said cup-shaped portion, a float valve resting on the bottom of said cup-shaped member over said aperture, a hard, cylindrical metallic disk disposed in said cup-shaped member between said float valve and nozzle, axially reciprocable in said cup-shaped member to impinge against said float valve and nozzle and being substantially coextensive with the internal diameter of said cup-shaped member and freely rotatable therein and having liquid passages along the edges thereof. ¹⁰
In testimony whereof I have affixed my signature to this specification.

WILLIAM M. ROGERS.
